UNITED STATES PATENT OFFICE.

OTTO ANDREAS ANDERSON, OF CHICAGO, ILLINOIS, ASSIGNOR TO THE ZANGERLE & PETERSON COMPANY, OF CHICAGO, ILLINOIS, A CORPORATION OF ILLINOIS.

DESIGN FOR A SETTEE FRAME OR SIMILAR ARTICLE.

Application filed January 28, 1929. Serial No. 29,804. Term of patent 3½ years.

To all whom it may concern:

Be it known that I, OTTO ANDREAS ANDERSON, a citizen of the United States, residing at Chicago, in the county of Cook and State of Illinois, have invented a new, original, and ornamental Design for a Settee Frame or Similar Article, of which the following is a specification, reference being had to the accompanying drawing, forming a part thereof.

The figure is a perspective view of a settee frame or similar article showing my new design. The design shown is carried across the front rail of the settee frame.

I claim:

The ornamental design for a settee frame or similar article as shown and described.

In witness whereof I hereunto set my hand this 21st day of January, 1929.

OTTO ANDREAS ANDERSON.
